UNITED STATES PATENT OFFICE.

FREDRICK W. BAUMGARTH, OF DETROIT, MICHIGAN.

PERMUTATION LOCK.

Application filed January 9, 1928. Serial No. 245,317.

The present invention pertains to a novel permutation or combination lock, and the principal object is to provide a device of this character which may be constructed of a 5 comparatively small number of simple parts and yet afford a large number of combinations, only one of which is correct. A further object of the invention is to apply the combination principle to household locks which 10 are now commonly operated by a key.

The device of the invention includes a plurality of rotatable disks having notches which are brought into registration on the proper setting of dials associated with the 15 disks. The bolt of the lock has a portion or a finger adapted to enter the notches when in registration. The bolt however cannot be moved unless the finger enters the notches, and it is therefore necessary that the latter 20 be brought into registration by exercise of the proper combination before it is possible to withdraw the bolt.

The invention is fully disclosed by way of example in the following description and 25 in the accompanying drawing, in which—

Fig. 1 is an elevation of a lock designed for use as a door lock;

Fig. 2 is a sectional view thereof in a parallel plane, showing the bolt projected;

30 Fig. 3 is a similar section showing the bolt withdrawn;

Fig. 4 is a transverse section on the line 4—4 of Figure 1;

Fig. 5 is an elevation of a modification; and

35 Fig. 6 is a transverse section on the line 6—6 of Figure 5.

Reference to these views will now be made by use of like characters which are employed to designate corresponding parts throughout.

40 The form shown in Figures 1 to 4 is to be carried within a door after the fashion of the conventional door lock. In this case a casing or housing 35 is inserted and fixed within the door 36. The casing contains 45 superposed notched disks 37 and 38, the former having a sleeve 39 extending beyond the face of the door and the latter having a stem 40 extending through the sleeve and beyond the free end thereof. To the face of the door 50 is applied a plate 41 bearing indicia 42 arranged in a circular series around the center of the stem and sleeve. The exterior part of the sleeve 39 is squared and has fixed thereto a dial 43 resting on the plate 41. The 55 extremity of the stem is also squared as at 44 for receiving a dial 45 laid upon the dial 43.

The disks are actuated by means of the dials, and the squared ends of the stem and sleeve permit four different adjustments of each dial, so that eight different combinations are 60 available.

Within the casing is mounted a slide 46, the forward edge of which is formed with a bolt 48 adapted to extend through the corresponding lateral wall of the casing. The opposite edge is formed with a projection or finger 49 adapted to enter the notches 50 of the disks when in registration with one another and in alignment with the path of the finger. The bolt is normally projected by a compressed 65 spring 51 inserted between the slide and the opposite wall of the casing and resting on fingers 52 and 53 projecting respectively from these parts.

The operating means for the slide includes 70 a lever 54 pivotally attached to the casing by a pin 55. The slide has a slot 56 receiving the pin in order to prevent obstruction of the movement of the slide. One end of the lever is adapted for engagement with a stud 57 75 formed on the slide. A cam 58 is also pivotally attached to the casing by a pin 59 and engages the other end of the lever. This pin is also received in a slot 60 formed in the slide for the purpose described in connection 80 with the slot 56. Externally of the casing, a finger piece 61 is secured to the pin 59 for the purpose of actuating the cam 58. After the notches 50 have been brought into registration adjacent the finger 49, the cam 58 may be 85 operated by the finger piece 61 to turn the lever 54 and thus move the slide and bolt to the position shown in Figure 3.

In Figures 5 and 6 is shown a modified construction wherein there is provided a single notched disk 70 having a stem 71 carrying a dial 72 outside the casing. The dial cooperates with a lettered plate 73 mounted on the member 36' in the manner described in connection with Figure 1. Apart from the 95 fact that this modification requires the setting of only one dial, the operation is exactly as described with reference to Figures 1 to 4.

Although specific embodiments of the invention have been illustrated and described, 105 it will be understood that various alterations in the details of construction may be made without departing from the scope of the invention as indicated by the appended claims.

What I claim is:—

1. A permutation lock comprising a casing, a plurality of notched disks rotatably mount-

ed therein, separate means outside of the casing for turning said disks, a slide mounted in the casing and having a finger adapted to enter the notches of the disks when in registration, a lever pivoted to said casing and adapted to move said slide, and a cam pivoted in the casing and adapted to swing said lever.

2. A permutation lock comprising a casing, a plurality of notched disks rotatably mounted therein, separate means outside of the casing for turning said disks, a slide mounted in the casing and having a finger adapted to enter the notches of the disks when in registration, a lever pivoted to said casing and adapted to move said slide, a cam pivoted in the casing and adapted to swing said lever, and a finger piece outside the casing and operatively connected to said cam.

3. A permutation lock comprising a casing, a plurality of notched disks rotatably mounted therein, separate means outside of the casing for turning said disks, a slide mounted in

the casing and having a finger adapted to enter the notches of the disks when in registration, a stud formed on said slide, a lever pivoted to the casing and having one end in engagement with said stud, and a cam pivoted in the casing and adapted to swing said lever.

4. A permutation lock comprising a casing, a plurality of notched disks rotatably mounted therein, separate means outside of the casing for turning said disks, a slide mounted in the casing and having a finger adapted to enter the notches of the disks when in registration, a stud formed on said slide, a lever pivoted to the casing and having one end in engagement with said stud, a cam pivoted in the casing and adapted to swing said lever, and a finger piece outside of said casing and operatively connected to said cam.

In testimony whereof I affix my signature.

FREDRICK W. BAUMGARTH.
